UNITED STATES PATENT OFFICE.

OTTO PETERMANN, OF GROTON, NEW YORK, ASSIGNEE TO STANDARD TYPEWRITER COMPANY, A CORPORATION OF NEW YORK.

TYPE-WRITING MACHINE.

1,081,145.

Specification of Letters Patent.

Patented Dec. 9, 1913.

Application filed September 13, 1913. Serial No. 789,625.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to a type-bar hanger or support for visible or front strike typewriting machines.

One of the principal objects of the invention is to provide a simple and efficient hanger for each type-bar which is so constructed as to provide a substantial bearing 15 for the type-bar and which is not liable to permit the bar to twist when operating the machine, thereby avoiding all unevenness in the alinement and overcoming many of the 20 objections incident to devices of this kind as ordinarily constructed.

Another object of the invention is to provide a simple and efficient support for the type-bar in which a relatively large bearing 25 surface is provided and in which adjustment may be readily secured in the direction of wear.

A further object of the invention is to provide a simple and efficient hanger or support 30 which may be formed substantially entirely from sheet metal and which may be made by dies and in such a way as to require very little if any machine work.

A still further object of the invention is 35 to provide a support for type-bars in which a central single pivot is provided for each bar and which pivot remains normally under tension in order that the type-bar may be securely held in the support.

A still further object of the invention is to 40 provide a hanger or support in which the pivot may be formed integral with one member of said support.

With these and other objects in view, the 45 invention will be hereinafter more particularly described with reference to the accompanying drawings, which form a part of this specification, and will then be pointed out in the claims at the end of the description.

In the drawings, Figure 1 is a fragmentary longitudinal section, partly in elevation, of a typewriting machine embodying one form of my invention. Fig. 2 is a detail side elevation of the hanger or support 55 showing the type-bar partly broken away. Fig. 3 is a vertical transverse section taken on the line III—III of Fig. 2; and Fig. 4 is a detail side elevation of the main supporting hanger member, looking in a direction opposite to Fig. 2.

While the invention is shown as applied to a visible typewriting machine in which the carriage is mounted upon a foldable support to adapt the platen and carriage to be folded 65 forward into overhanging relation to the keyboard, it will be understood that the invention may be applied to various types of writing machines.

The frame 10 may be of any suitable construction and may have a transversely extending bar or plate 11 at the rear thereof. A plurality of supports 12, only one being shown, in the form of rods extend transversely of the machine between the sides of 75 the frame 10, and pivotally mounted on these rods are the key-operated levers 13 forming a part of the usual keyboard. The key-operated levers 13 are each normally forced in one direction by a spring 14 and 80 at their inner or rear ends are each connected by a link 15 to a type-bar 16. The type-bars 16 have type heads or blocks 17 on which are a plurality of characters indicating the upper and lower case and figures, 85 etc. The type-bars 16 are adapted to be moved against the work sheet on the platen 18 as each key-operated lever 13 is depressed in the usual way. The platen 18 is mounted upon a carriage 19, which is adapted to 90 travel along a bed 20. The bed 20 is held to bars 20 forming a part of a foldable support which adapts the carriage and platen to be folded forward into overhanging relation to the keyboard.

The parts thus far described may be of the usual or of any preferred construction.

A hanger 21 or other support is provided for each type-bar 16. These hangers each comprise two members 22 and 23. The 100

member 22 has a plate-like body with feet 24 at an angle thereto in which are openings 25. Screws 26 have their bodies passing through the openings 25 and serve to rigidly hold the hangers to the supporting plate 11 of the frame. The hanger member 22 is provided with an annular rib 27 formed by depressing a portion of the body thereof, and resting directly against said rib is an 10 annular rib 28 of the type-bar 16. The type-bar 16 has an enlarged head or boss 29 and may also have its rib 28 formed by depressing a part of the head 29 in the manner shown. The type-bar has its rib 28 opposed 15 to the rib 27 so as to form an annular space or chamber 30 in which a suitable lubricant may be placed if desired, and said type-bar has its head located in the space 31 formed between the hanger members 22 and 23. By 20 providing the ribs a large substantial bearing surface with little friction is provided, and said bearing surface may be readily ground to provide suitable surfaces instead of grinding the entire faces of the hanger 25 member and the type-bar head.

The member or strap 23 of the hanger may be made of lighter metal than the member 22 and may be of spring material and has one end, as 32, provided for an aperture 30 through which passes the body of the screw 33, in order that said member 23 may be held to the member 22. The member 23 at the end 32 may also be provided with depressed parts, as 34, forming dowel pins 35 which are adapted to enter recesses 34^a in the member 22 to assist in holding the member 23 against swinging movement and in proper position relative to the member 22. This member 23 is offset at 35 to provide the 40 space 31 for the type-bar boss, and has a vertical portion 36 from which may be depressed a substantially semi-spherical member or body 37. The body 37 is located at the free end of the member 23 and performs 45 the same function as a ball pivot except that it is immovable in a rotary direction, and said body 37 is adapted to be seated in a conical or cup-shaped recess or opening 38 formed in the type-bar head or boss 29. The 50 recess or opening 38 tapers from the outside of the type-bar inward and is so arranged with respect to the member 37 that a bearing or pivot for the type-bar is provided at one point and that on the side opposite the 55 member 22 of the hanger or support. A screw 39 has its stem portion passing through a central aperture of the pivot or integral bearing body 37 and engages a threaded aperture in the member 22, said screw and body 37 being substantially central of the boss or head 29 of the type-bar. The screw 60 39 has a slotted hexagonal head to adapt the same to be adjusted by either a wrench

or a screw-driver. The screw 39 is normally held under tension by reason of the spring 65 action of the member 23, and in addition to this tension or independent thereof the said screw may be held at its threaded end where it engages the threaded opening in the member 22. A slot 40 may extend on opposite 70 sides of the threaded opening for the screw, and a part of the member 22 may be cut away at one side of said opening, as at 41, to form a yielding part or finger 42. This yielding part will keep the screw under tension 75 and prevent the same from becoming loose, while the machine is in use, and further the original tight fit of the screw will be maintained. By rotating the screw the member 23 may be forced toward the member 22, and will carry the type-bar therewith in order that the wear may be taken up in case it occurs and the type-bar forced 80 properly against the hanger member 22.

It will be evident that by providing a 85 hanger or a support in which a single pivot is provided for each type-bar and in which the pivot portion is forced in the direction 90 of wear by means located at the pivot, all liability of the type-bar to twist when operating the machine which may cause unevenness in the alinement is overcome; that the ribs form means providing a substantial bearing; that said hanger or support is simple in construction and may be made by 95 stamping the same from sheet metal; and that effective means is provided whereby the operating surface between the hanger and the type-bar may be properly lubricated.

Having thus described my invention I 100 claim as new and desire to secure by Letters Patent:—

1. The combination of a plate-like hanger member having means for securing the same to a support and having an annular rib on 105 one side thereof, a plate-like spring member secured at one end to the first-mentioned member and offset therefrom and provided with an integral cup-shaped body forming a bearing, a type-bar having an annular rib 110 on one side bearing directly against the rib of the first-mentioned member and having a tapering opening receiving the body of the spring member, and a screw passing centrally through the cup-shaped bearing, the 115 body of the spring member, and the type-bar, and held to the first-mentioned hanger member for adjusting the plate-like spring member and bearing portion in the direction of wear.

2. The combination of a plate-like member having means for securing the same to a support and having an annular rib on one side thereof, a plate-like yielding member secured at one end to the first-mentioned 125 member and offset therefrom, a body form-

- ing a bearing carried by the yielding member at its free end, a type-bar having an annular rib on one side bearing directly against the rib of the first-mentioned member and having a tapering opening receiving the body of the yielding member, and means passing through the body and serving as means for forcing the members toward each other.
10. 3. The combination of a member having means for securing the same to a support and having an annular rib on one side thereof, and a plate-like member secured at one end to the first-mentioned member and offset therefrom and provided with a cup-shaped body forming a bearing at its free end, a type-bar having an annular rib on one side bearing directly against the rib of the first-mentioned member and having a tapering opening receiving the body of the plate-like member, and a screw passing centrally through the cup-shaped bearing, the type-bar and said members.
4. The combination of a plate-like member having means for securing the same to a support and provided with a bearing rib, a plate-like member secured at one end to the first-mentioned member and offset therefrom and provided with an integral cup-shaped body forming a bearing, a type-bar bearing directly against the rib of the first-mentioned member and having a tapering opening receiving the body of the second member, and means for adjusting the members in the direction of wear.
5. The combination of a member having means for securing same to a support and having an annular rib on one side thereof, a second member secured at one end to the first mentioned member and offset therefrom and provided with a cup-shaped body forming a bearing at its free end, a type-bar bearing directly against the rib of the first-mentioned member and receiving the cup-shaped body of the second member, and a screw passing centrally through the cup-shaped body, the type-bar and the said member.
6. The combination of a support having two members, a pivot movable with one member only, a type-bar supported by said pivot on one side only thereof, and adjusting means passing through the pivot to take up wear.
7. The combination of a support having an annular bearing rib, a type-bar having an annular rib bearing directly against the rib of the support and forming an interior annular chamber, and a member forming a part of the support and having means serving as a pivot for the type-bar at one side thereof.
8. The combination of a support having an annular bearing rib, a type-bar bearing directly against the rib or support at one side, and a yielding member forming a part 65 of the support and having an integral cone serving as a pivot for the type-bar at one side thereof and substantially central of the bearing rib.
9. The combination of a hanger member 70 having an annular bearing rib, a type-bar having an annular rib bearing directly against the rib of the support and forming an interior annular chamber, and a second hanger member held to the first-mentioned 75 member and having an integral pivot for the type-bar at one side thereof.
10. The combination of a support having an annular bearing rib, a type-bar having an annular rib bearing directly against the 80 rib of the support, a pivot for the type-bar, and adjusting means passing through the pivot.
11. The combination of a hanger comprising two members, one of which is provided 85 with feet adapted to be secured to a support and the other of spring metal and having an integral body projecting therefrom, a type-bar supported by said body as a pivot and bearing directly against one of the members 90 of the hanger only, and means for adjusting the spring member toward the other member.
12. The combination of a hanger comprising two members, one of which is adapted to 95 be secured to a support and the other of spring metal and having a body carried thereby at one end, a type-bar supported by said body as a pivot and bearing directly against one of the members of the hanger, 100 and means for adjusting the spring member toward the other member.
13. The combination of a hanger comprising two members, one of which is adapted to be secured to a support and the other of 105 spring metal and having an integral semi-spherical body projecting therefrom at one end, a type-bar supported by said body as a pivot, and a screw passing through the pivot for adjusting the spring member toward the 110 other member.
14. The combination of a hanger comprising two members, one of which is provided with feet adapted to be secured to a support and the other having an integral pivot body 115 projecting therefrom at one end, a type-bar supported by said body as a pivot and bearing directly against one of the members of the hanger only, and a screw passing through said body for adjusting the mem- 120 bers.
15. The combination of a support having two relatively adjustable members, a type-bar having a flat bearing at one side only bearing against one member, means movable 125 with the other member forming a pivot

4
bearing for the type-bar at the other side only, and an adjusting screw engaging both members and passing through the pivoting means.

5 16. The combination of a support having a plurality of members one of which has a threaded opening and a yielding finger into which said threaded opening extends, a type-bar, and a screw engaging said threaded opening and held under tension, said

screw passing through the type-bar and serving as a means for forcing the members toward each other.

This specification signed and witnessed this 6th day of Sept. A. D. 1913.

OTTO PETERMANN.
